UNITED STATES PATENT OFFICE.

FRANK E. CURTS, OF OMAHA, NEBRASKA, ASSIGNOR TO WALDO E. HIKES, OF CHICAGO, ILLINOIS.

AUTOMATIC OIL-CONTROLLER.

1,237,621.

Specification of Letters Patent.

Patented Aug. 21, 1917.

Application filed January 18, 1917. Serial No. 142,304.

To all whom it may concern:

Be it known that I, FRANK E. CURTS, a citizen of the United States, and a resident of Omaha, in the county of Douglas and 5 State of Nebraska, have invented certain new and useful Improvements in Automatic Oil-Controllers, of which the following is a specification.

My invention relates to devices for controlling a supply of lubricating-oil to internal-combustion engines, and particularly such engines as are used in motor-vehicles. It is the object of my invention to provide means for automatically maintaining a substantially constant quantity of lubricating-oil in the crank-case of an engine of the described class, regardless of the disturbance of the oil-level occasioned by splashing thereof when the engine is running. A further object of my invention is to provide means for automatically replenishing the supply of lubricating-oil in the engine crank-case, so as to maintain a normal quiescent level thereof. A further object of my invention is to provide means for automatically preventing operation of the oil-replenishing means whenever the engine is running. More detailed objects of the invention will appear hereinafter.

30 In the accompanying drawings, Figure 1 is a side view of an engine provided with oil-supplying and controlling means embodying my invention, Fig. 2 is a detail vertical sectional view of the oil-controller, 35 Fig. 3 is a detail plan view of the same, and Fig. 4 is a transverse section thereof looking upwardly from the horizontal plane of the line 4—4 of Fig. 2.

In many engines of the class commonly used in motor-vehicles, the principal lubrication thereof is afforded by a supply of oil carried in the crank-case of the engine and splashed onto the moving parts by the movements of the crank-shaft and connecting-rods during running of the engine. To secure efficient lubrication of the engine it is essential that a substantially constant quantity of oil be maintained in the crank-case; since if the amount of oil is too great it will be wasted by burning in the cylinders, causing carbon deposits therein and disagreeable fumes in the exhaust; while if the amount of oil is insufficient the parts will not be properly lubricated. The amount of oil in the crank-case can be definitely ascertained only

when the engine is not running, and then, as the body of oil assumes a quiescent level, the amount is readily shown by the use of a gage-glass or the like. At such times a simple float-controlled valve, adjusted so as to close when the oil is at or above the desired normal level, will serve to control the admission of oil from a suitable storage reservoir, but such a valve, if used by itself, would permit flooding of the engine with oil when the normal or quiescent level was lowered by splashing thereof during running of the engine.

In the illustrated embodiment of my invention there is provided a means for storing a supply of oil and delivering the same under moderate pressure, comprising a tank 5 supported at a suitable elevation and connected by means of a pipe 6 with the controlling valve-mechanism. The latter has a casing of which the main body 7 is substantially cylindrical and incloses a float-chamber 8. The upper end of the float-chamber is closed by a head 9 removably secured to the body 7 by screws 10. At one side of the casing there is a threaded opening for receiving the end of a short pipe 11, the same extending into a similar opening in the lower portion of the engine crank-case A and thereby connecting the float-chamber 8 with the oil-chamber in said crank-case. At one side of the body 7 there is a projecting vertically-perforate lug 12 through which is passed the lower end-portion of a small supporting-rod 13, the same being threaded and provided with suitable nuts 14 above and below the lug, and the upper end of the rod having a laterally extending eye which is secured to the engine by means of one of the casing-bolts B. At one side of the body 7 a small gage-glass or column 15 is connected therewith by means of a pipe-nipple 16, and a drain-cock 17 may also be provided in connection with the gage, as shown. The gage, of course, shows the oil-level in the float-chamber. At the lower end of the chambered body 7 there is an integral projecting portion 18 inclosing a valve-chamber 19 which is shouldered at its intermediate portion to provide a seat 20 for a valve 21. The lower end of the valve-chamber has a plug 22 screwed therein, said plug having a threaded central opening for receiving the end of a tubular sleeve 23 with which the oil-supply pipe 6 is con-

nected. The upper end of the valve-chamber is connected by diagonal passages 24 with the float-chamber 8. The valve 21 is screwed onto the threaded lower terminal portion of a stem 25, the valve preferably having a facing-disk 26 of leather or the like for bearing against the seat 20, and said disk 26 being held thereon by a washer 27 resting against the shoulder at the upper end of the threaded portion of the stem 25. A small locknut 28 is also provided on the lower end of the stem to prevent loosening of the valve thereon. A sleeve 29, fitting upon the valve-stem above the washer 27, 15 extends slidably through a vertical opening between the passages 24 into the lower end of the float-chamber, and supports at its upper end a washer 30 which bears against the lower side of the float 31. The valve-stem 25 extends axially through the float, and at its upper end has a relatively wide flat head 32. Beneath said head a sleeve 33 is disposed around the stem, the lower end of said sleeve engaging a washer 34 25 which bears against the upper end of the float. The float and valve are so proportioned and arranged that when there is the desired level of oil in the float-chamber the float will raise the valve against the seat 20, as shown in Fig. 2, and shut off the flow of oil from the pipe 6 to the float-chamber.

The head 9 of the chambered body 7 has an upwardly projecting central portion having formed in the lower part thereof a small cylinder 35 in which a piston or plunger 36 is fitted so as to be vertically slidably therein. A small coil spring 37 is disposed within the upper part of the cylinder, extending up into a recess in a projecting nipple 38 at the end thereof. Said spring normally presses the plunger down into engagement with stops formed by washers 39 which are secured on the lower side of the head 9 by screws 40, as shown. The lower end of the plunger 36 is cylindrically recessed, and two flat springs 41 are secured thereto so as to extend in radially from the sides thereof toward the center, the outer ends of the springs lying in notches in the edge of the plunger and having portions of the material swaged in around them to retain them in the notches. The valve-stem and sleeve 33 extend between the adjacent ends of the springs 41, so that the head 32 of the stem lies above the inner terminal portions of the springs. The depth of the recess in the plunger is sufficient to permit normal vertical movements of the valve-stem and float, when the plunger is in its normal lower position against the stops 39, without the head 32 engaging either the springs or the top portion of the plunger. When the plunger is moved upwardly to 60 engagement with the shoulder at the end of

the cylinder 35, as shown by dotted lines in Fig. 2, the springs 41 engage the head 32 of the valve-stem and retain the same in the raised position at which the valve is closed, the springs being slightly bent when 70 the plunger is at its limit of upward movement. The nipple 38 is internally threaded to receive a tubular elbow 42, and from the latter a small pipe or tube 43 is extended to and connected with the intake manifold-pipe 75 D of the engine at a point between the carbureter C and the engine cylinders.

In the head of the float-chamber there is a small air-vent 44, so that the lower end of the plunger 36 is constantly subject to atmospheric pressure. When the engine is running the suction from its cylinders causes a considerable reduction of air-pressure in the intake-pipe D, and as the latter is in communication with the cylinder 35, through 80 the pipe 43, there is a similar reduction of air-pressure upon the upper end of the plunger 36, causing the same to be drawn up to the position shown by dotted lines in Fig. 2. When the engine is stopped the pressure 90 equilibrium upon the plunger is immediately restored, and the spring 37 moves the plunger down to its normal lower position.

From the foregoing the operation of the oil-controller as a whole will be clearly apparent. When the engine is not running the oil in the crank-case assumes its normal quiescent level, and said level will be the same in the float-chamber 8 and gage 15, the oil flowing through the connecting pipes 11 and 16. Should the oil-level be below the normal, the float 31 will drop sufficiently to open the valve and permit a flow of oil from the storage-tank 5 until the level is restored to the normal, when the float will be raised to close the valve and stop the supply from the tank. When the engine is started, the suction in the pipe D lifts the plunger 36 and holds the valve in closed position until the engine is stopped, whereupon the valve 100 is freed so that automatic replenishment of the oil-supply may occur by the operation of the float. It may be noted that movement of air through the pipe 43 is only momentary, occurring merely at the times that the 110 engine is started or stopped, since when the plunger is lifted by the suction thereon it engages the shoulder at the upper end of the cylinder 35, seating on said shoulder like a valve, so as to prevent leakage of air past 115 the same. The slightly resilient connection between the plunger and valve-stem, afforded by the springs 41, enables the plunger to have a slight movement in excess of that required to firmly close the oil-valve, to insure engagement of the plunger with the end of its cylinder without liability of the oil-valve being left open. As but a comparatively small amount of lubricating-oil is 120 actually consumed by the engine of a motor- 125 130

vehicle during such periods of time as the engine would ordinarily be run continuously, it will be apparent that the described device, by automatically replenishing the oil-supply whenever the engine is stopped, provides a simple and positive means for maintaining a substantially constant amount of oil in the crank-case.

Now, having described my invention, what I claim and desire to secure by Letters Patent is:

1. The combination with an engine having a lubricating-oil chamber in which the oil-level is altered during running of the engine, of an oil-storage receptacle connected with said chamber, a valve controlling the flow of oil from said receptacle to said chamber, means normally controlling said valve to open and close the same in accordance with changes of the oil-level in the chamber, and means for automatically retaining said controlling means in valve-closing position during running of the engine.
2. In a lubricating-oil controller for engines of the class described, a source of oil-supply, a valve normally controlling flow of oil from said source to a receiving-chamber in accordance with changes of oil-level in said chamber, and means for automatically retaining said valve in closed position during running of the engine.
3. In a lubricating-oil controller for engines of the class described, a source for supplying oil under pressure to a receiving-chamber, means for automatically preventing flow of oil to said chamber from said source when the oil in said chamber is above a predetermined level, and means for automatically preventing the flow of oil to said chamber from said source when the engine is running.
4. In a lubricating-oil controller for engines of the described class, means for supplying oil to a receiving-chamber, a float-controlled valve associated with said chamber

and normally controlling the flow of oil thereto, and means for automatically holding said valve closed when the engine is running.

5. The combination with an internal-combustion engine having an inlet-pipe and a chamber for lubricating-oil, of a source for supplying oil to said chamber, a valve controlling flow of oil from said source to said chamber, actuating means for closing and opening said valve normally in accordance with the rise and fall of the oil-level in said chamber, and valve-actuating means dominating the first-named actuating means therefor and controlled by variations of pressure in the inlet-pipe.

6. The combination with an internal-combustion engine having a charge-inlet pipe and a chamber for lubricating oil, of a source for supplying oil to said chamber, a valve controlling flow of oil from said source to said chamber, a float associated with said chamber and valve and normally movable by changes of oil-level in the chamber to open and close the valve, and a means for actuating said float controlled by variations of pressure in the charge-inlet pipe of the engine.

7. The combination with an internal-combustion engine having a charge-inlet pipe and a chamber for lubricating-oil, of a source for supplying oil to said chamber, a valve controlling flow of oil from said source to said chamber, a float associated with said valve and chamber and normally actuating the valve to closed position when the oil rises to a predetermined level in the chamber, and air-pressure-actuated valve-controlling means connected with the charge-inlet pipe and adapted to retain the valve in closed position when the pressure in the charge-inlet pipe is below atmospheric pressure.

FRANK E. CURTS.
